UNITED STATES PATENT OFFICE

WILLIAM E. LEIBING, OF SAUSALITO, CALIFORNIA, ASSIGNOR TO LYON-MAGNUS INCORPORATED, OF SAN FRANCISCO, CALIFORNIA, A CORPORATION OF DELAWARE

COOLING SYSTEM FOR BEVERAGE DISPENSING APPARATUS

Application filed February 19, 1930. Serial No. 429,686.

This invention relates to a cooling system for beverage dispensing apparatus in which the beverage passes through containers or pipes, which are immersed in a cooling bath to maintain the beverage dispensed at a desired temperature.

In the dispensing of beverages, it is the usual practice to pass the pipe for the beverage through a cooling bath that is provided at one point with means for maintaining the cooling bath at a lowered temperature. This apparatus usually includes an ice container positioned in the cooling bath or a mechanically, electrically or other suitably operated cooling unit immersed in the bath, which unit is provided with means to automatically maintain the cooling coils thereof at a desired temperature. In order that the pipes through which the liquid to be dispensed passes may be maintained at a low temperature, it is usually desirable that the liquid bath be circulated in some manner, since it is found that otherwise the temperature thereof will be relatively low adjacent the cooling unit, while the temperature of the bath adjacent the dispensing pipe will be comparatively high.

To avoid this undesirable condition attempts have been made to provide a circulating means for the cooling bath of the above described apparatus, but such attempts have been only partially successful in accomplishing the desired results, and have usually had serious defects in their operation. In one form of such proposed circulating means, a small electric pump, provided in the bath, is constantly driven to maintain a circulation of the bath. This apparatus is expensive to install and expensive to operate, and has a defect in operation in that if the attendant fails to cut off the circulating pump when the soda fountain or the like is closed for the night, the bath will be continuously circulated during the period when there is no dispensing liquid passing through the pipes, and, therefore, no means to give up heat to the bath, and the refrigerating unit will thus continue to operate and the liquid in the dispensing pipe may become frozen so that the pipes will break.

A primary object of this invention, therefore, is to provide a cooling system for dispensing beverages in which the bath surrounding the pipes of the dispensing apparatus is maintained at a uniformly low temperature by agitation and circulation in direct accordance with, and in proportion to, the amount of liquid dispensed. 55

Another object of this invention is to provide a circulating and agitating means for 60 the bath of a dispensing apparatus, which is simple and inexpensive to install, and which does not require any specially supplied source of energy, such as electric current for operating the same. 65

In the modern soda fountain, as built today, it is also customary to provide a cooling bath, through which the pipes for the liquid to be dispensed pass, with a mechanical cooling unit immersed in said bath for cooling 70 the same. Usually the various syrups for the drinks dispensed at the fountain are positioned in small containers adjacent the top of the soda fountain for ready access. It is very desirable that these syrup containers be 75 also cooled, but due to the fact that the syrup containers are positioned well above the usual cooling bath, the problem of cooling them has been found to be a troublesome one. In some instances, cooling coils from the refrigerating unit have been passed through the bath in which the bottoms of the syrup containers are immersed for cooling the same, but such apparatus is expensive to install and is also relatively inefficient to operate. 80

Another object of this invention, therefore, is to provide a soda fountain, wherein a plurality of syrup containers are positioned adjacent the top of the fountain, with simple and inexpensive means associated 90 therewith for cooling the syrup containers.

Another object of this invention is to provide a soda fountain, having a plurality of syrup containers, with simple and inexpensive means whereby the cooling bath, normally used to maintain the pipe of the dispensed liquid at the proper temperature, may be circulated through a bath for the syrup containers for maintaining said containers at a desired temperature by the action of a fluid 100

motor operated by the flow through said pipe.

Another object of this invention is to provide a soda fountain having embodied therein an easily installed device, which has substantially no upkeep expense, for agitating the cooling bath surrounding the dispensing pipe in accordance with the amount of fluid dispensed, and further having means for circulating a portion of the cooling bath around the syrup containers for maintaining said containers at a desired temperature.

These and various further objects of the invention will be apparent from the following description and from the accompanying claims, when taken in connection with the drawings wherein—

Figure 1 is a cross-section of a cooling bath for the pipes of a dispensing beverage apparatus with one embodiment of my novel agitating means therein.

Figure 2 is an elevation of the agitator shown in Figure 1 with the cover thereof removed.

Figure 3 is a section on line 3—3 of Figure 2.

Figure 4 is a cross-section of a soda fountain showing another embodiment of my improved agitator for the bath, with novel means for cooling the syrup containers thereof.

Figure 5 is a sectional view of the combined agitator and circulating pump as used with the soda fountain of Figure 4, and

Figure 6 is a section on line 6—6 of Figure 5.

Referring to Figure 1, I have illustrated an apparatus for dispensing beverages of any nature such as orangeade, lemonade, root beer, or carbonated or plain water. As illustrated there are two pipes 1 for the liquids to be dispensed, sections of which extend into and are immersed in the cooling bath 2 said pipes being connected to tanks 3 which contain the liquids to be dispensed, and which are connected at their lower ends by pipes 4 with a source of supply of the liquid. It will, of course, be understood that the invention is not limited to the use of two dispensing pipes within the bath, since one or any number of such pipes may be used. Also, it will be understood that the dispensing liquids may pass through a coil positioned within the bath instead of passing through the tanks 3. The bath 2 is positioned within a receptacle having the outer and inner walls 5 preferably covered with heat insulating material 6 of any character.

An automatically controlled mechanical refrigerating unit 7 is positioned within the bath 2 and has depending pipes 8 thereon with the cooling fins 9 associated therewith. This mechanical refrigerating unit may be electrically or mechanically operated. The coils 8 and the fins 9 thereof extract the heat from the surrounding bath in known manner. It is found that the dispensing pipes 1, and the

tanks 3, are not maintained at desired temperatures when the bath depends merely upon the thermo-syphon action thereof to maintain a substantially uniform temperature of the liquid.

To overcome this difficulty, I have interposed in the dispensing lines 1 bath agitators which are operated by the flow of liquid to be dispensed. Each agitator includes a casting 12 having threaded ends 13 for attachment to the pipe line 1, there being a passage-way 14 through each of the threaded portions 13 and casting 12, said passage-way being connected at a tangent to a circular chamber within casing 15. The casing 15 is shown as being formed integrally with the casting 12, and, as seen in Figure 3, it is offset from the axis of the passage-way 14. Casing 15 is provided with an annular flange 16 for the reception of a cover plate 17 secured thereto by retaining bolts 18, with a gasket interposed therebetween.

The casing 15 has an outstanding centrally positioned boss 19, and an inwardly extending annular flange 22, providing a bearing for a rotary shaft 23. The cover member 17 has also a centrally positioned bearing 24 for the outer end of shaft 23.

Secured to rotary shaft 23 and positioned within the casing 15 is a rotor 25. The rotor 25 extends closely adjacent the rim of the circular casing 15 and has outstanding blades 26 thereon.

The blades 26 extend into the passage-way 14 as seen in Figure 2, whereby flow of the dispensing liquid in the direction indicated by the arrow of Figure 2, will cause the rotor 25 to be turned. It will be noted that the pockets in the rotor are of substantially the same depth as the diameter of passage-way 14, and that the blades 26 are substantially at right angles to the direction of flow, with the result that the rotor will attain a peripheral speed substantially equal to the velocity of the dispensing liquid.

The shaft 24 has a fan 27 on the outer end thereof that is normally immersed in the bath 2 to circulate the same. A packing 28 is positioned within the hub 19 and maintained in liquid tight engagement against flange 22 by a packing ring 29 engaged by a coil spring 32 the opposite end of which is engaged by a packing compression screw 33 threaded into hub 19. The packing compression screw 33 has an integral hub 34 which engages packing ring 29, whereby the packing 28 may be compressed by rotating member 33, the spring 32 always taking up lost motion and maintaining the packing tight.

The operation of my system is as follows. With the refrigerating unit in operation the coils 8 having cooling fins 9 thereon will generate ice in the bath 2, as seen in Figure 1. However, due to the fact that the water of the bath is a poor conductor of heat, the pipes

1 and tanks 3 for the liquid to be dispensed may be relatively warm, and especially so during rush periods when the liquid is being rapidly dispensed and flow through pipes 1 and tanks 3 is almost continuous, unless agitating means is provided for stirring the bath 2. With my agitators connected in the pipelines 1, the rotors 25 will be turned and the agitating fans 27 will be rotated in proportion to the demands upon the system. During periods of heavy demand, the bath 2 will be almost continuously agitated and the temperature of the liquid dispensed will be about 38° F. at the dispensing valve when the temperature of the entering liquid is about 70° F.

It will be obvious that the casting 12 having the impellor or rotor 25 could be positioned exterior to the bath 2 with suitable mechanical connections whereby the agitator 27 is within the bath. Also, the pipes 1 may be coiled within the bath instead of being connected to tanks 3 therein.

In Figures 4, 5 and 6 I have shown a system in which a rotor similar to that shown in Figures 1 to 3 is used, said rotor being adapted to drive two separate means for circulating the cooling liquid of the bath, one of said means consisting of the fan immersed in the bath, and the other of said means including a pump for causing the positive circulation of the liquid of said bath. Figure 4 shows a preferred embodiment of my apparatus in connection with a soda fountain, but it will be understood that the novel means for causing circulation and agitation of the bath may be used in various other forms of apparatus. Referring to Figure 4, the soda fountain includes a refrigerating unit 7 having the depending pipes 8 thereon immersed in the bath 2, said bath being enclosed within walls 32 with suitable insulation 33 surrounding the same, and contained within the outer walls 34, the front and top of which may be marble or the like. As is usual in this type of structure, the soda fountain extends upwardly adjacent the front side thereof and a marble top 35 is positioned thereon with the insulation 36 beneath the same.

As shown in Figure 4, the fountain has two tanks 37 therein, one of which may be used in dispensing plain water, and the other of which may be used in dispensing carbonated water. The tanks 37 have outlet pipes 38 thereon connected to the liquid supply lines. Said tanks are connected by pipes 39 to the dispensing nozzles 41, there being only one pipe 39 and one nozzle 41 shown in Figure 4 for the sake of clearness. Positioned at an angle in the upwardly extending portion of the soda fountain are a plurality of syrup containers 42, having dispensing nozzles 43 thereon, said containers extending at an angle into an auxiliary or secondary cooling bath 44 in a container 45

positioned above the main bath 2. The secondary bath 44 is open at its top and extends lengthwise of the fountain, a spider frame work 46 removably supporting the syrup containers 42 with their lower ends positioned within the auxiliary bath 44. A plurality of crushed fruit containers 47 may be so positioned that their lower ends extend into the main cooling bath 2.

Due to the necessity for conservation of space and ready accessibility it is usual for the syrup containers 42 to be positioned as shown above the main cooling bath 2 and these containers do not accordingly extend into the main bath. The syrup containers are not sufficiently cooled by the rising air from the bath 2, and relatively expensive means have been proposed to provide auxiliary cooling means around these containers. In order that the auxiliary bath may be sufficiently cooled to maintain the syrup in the containers in proper condition, I provide a mechanism which operates in conjunction with the flow of liquid through the main dispensing pipes 39 to provide a positive circulation of the cooling liquid from the main bath 2 to the secondary bath 44. This mechanism is shown in detail in Figures 5 and 6.

A dispensing pipe line 39 has preferably positioned therein a casting 12, similar to that shown in Figure 2, in which is positioned a rotor 25 having the blades 26 thereon and mounted on the shaft 23. Shaft 23 extends beyond the open end of the central hub 19 of casing 15 and has secured on the outer end thereof the agitating fan 27.

Removably secured to the hub 19 by a set screw 47 is a pump housing 48. The pump housing 48 is flared outwardly to provide a casing 49 and has an outstanding annular flange 51 adapted to receive a cover 52, bolts 53 securing the cover 52 in fluid-tight engagement with flange 51, with a gasket interposed therebetween. The cover 52 is provided with an enlarged central opening 54 through which the shaft 23 extends, and the hub 56 of a rotor 57 of a centrifugal pump is secured to shaft 23 by set screw 55. The rotor 57 has a plurality of blades 58 thereon and the casing 49 has a threaded outlet 59 for the reception of a correspondingly threaded pipe.

The pump housing 48 has a plurality of openings 61 adjacent the head 33 of the packing adjusting screw, whereby access may be had to said screw for tightening the packing gland. By the above described construction it will be clear that rotation of the rotor 25 by flow of fluid in the pipe 39 will cause rotation of the pump rotor 57 and the fan agitator 27.

The fan 27 is immersed in the main bath 2 of the soda fountain, and the outlet 59 of the centrifugal pump is connected to a pipe 62 which extends across the bath 2 and

has its open end positioned just above the secondary bath 44 for discharge into said bath. An overflow pipe 63 is connected to the secondary bath 44 and extends downwardly and discharges into the main bath 2.

When taken in connection with Figures 1, 2 and 3, it is believed that the operation of the cooling system shown in Figures 4 to 6 will be obvious. When any liquid is dispensed through the pipes 38, tanks 37, pipes 39, and nozzles 41, the rotor 25 will be actuated and the fan agitator 27 will rotate and the centrifugal pump 57 will also be rotated. Liquid from the main bath 2 will thus be sucked into the pump through the opening 54 in the cover 52 and by way of openings 62 in the casing 49 and said liquid will pass by way of the outlet 59 and pipe 62 into the secondary bath 44. It will be understood that the bath 44 extends longitudinally of the entire soda fountain and the inlet pipe 62 and the outlet pipe 63 will communicate therewith at opposite ends. Therefore, cooling liquid from the main bath 2 which has been refrigerated by the refrigerating unit 7 will be circulated to the auxiliary bath 44 to maintain the syrup-containers 42 at a desired temperature. Simultaneously the main bath 2 will be maintained at a constant and even temperature by rotation of the agitating fan 27.

Although I have shown only one casting 12 in the main bath 2 of Figure 4 for the sake of clearness, it will be understood that such casting with the agitator and pump associated therewith may be positioned in each dispensing pipe 39.

Thus it will be seen that the apparatus shown in Figures 4 to 6 provides a dual means for maintaining the bath at a constant temperature. The rotary fan 27 operates as previously described in connection with Figures 1 to 3 and the centrifugal pump 57 further operates to provide a positive circulation of the liquid of the bath 2. In some installations it may be found desirable to provide only one of these dual circulating means, in which case the agitating fan 27 may be omitted, and the centrifugal pump 57 may provide sufficient circulation for the main bath 2. If the dispensing system is not of the typical soda fountain type wherein the syrup containers are used, there will of course be no necessity for providing the auxiliary bath 44, and the centrifugal pump 57 may discharge into the main bath 2 directly at a distant point from the inlet of said pump. By this construction the liquid of the main bath 2 will be constantly circulated and will thus be maintained at an even temperature. However, when the usual soda fountain is to be used it will generally be found desirable to provide both types of agitating and circulating means for the bath 2.

With my apparatus connected as above described, the danger of freezing the entire system during over-night rest periods is eliminated since the bath water 2 is circulated in direct proportion to the amount of liquid dispensed and is not actuated when no liquid is dispensed. Therefore the temperature of the bath adjacent the dispensing pipes is not lowered below freezing by a continual circulation when no liquid is being dispensed, and maximum circulation takes place during maximum demand periods.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What I claim and desire to secure by United States Letters Patent is:

1. In a liquid dispensing apparatus, a cooling bath, means conducting liquid to be dispensed, and means operable in response to flow of liquid through said first named means for agitating said bath.

2. The invention as defined in claim 1, wherein said second means includes a rotor operated by flow of said liquid.

3. The invention as defined in claim 1, wherein said means for conducting the liquid includes a pipe, and said second means includes a rotor operated by passage of liquid through said pipe, and blades within said bath connected to and rotated by said rotor.

4. In a liquid dispensing apparatus, a cooling bath, a pipe line for conducting the liquid to be dispensed, said pipe line being partially immersed in said bath, a casing connected in said pipe line and having a rotor therein for rotation by the flow in said pipe line, a shaft connected to said rotor, and an agitator immersed in said bath and operated by said shaft.

5. The invention as defined in claim 4, wherein an automatically operated and controlled refrigerating unit is immersed in said bath.

6. In a liquid dispensing apparatus, a cooling bath, means for conducting liquid to be dispensed, said means being partially immersed in said bath, and dual bath agitating means operable in response to flow of liquid through said liquid conducting means, one of said means agitating said bath, and the other of said means causing a positive circulation thereof.

7. In a liquid dispensing apparatus, a main cooling bath, means in said bath for conducting liquid to be dispensed, a secondary cooling bath, and means operable in response to

flow of liquid through said first named means for causing a positive circulation between said main bath and said secondary bath.

8. In a liquid dispensing apparatus, a main cooling bath, a pipe for conducting liquid to be dispensed through a portion of said bath, a secondary cooling bath, a rotor operated in response to flow of liquid in said pipe, and means connected to said rotor for causing a positive circulation between said main bath and said secondary bath.

9. The invention as defined in claim 8, wherein an agitator is positioned in said main bath and operated by said rotor.

10. In a soda fountain, a main cooling bath, a refrigerating unit therein, a pipe line for conducting liquid to be dispensed through said bath, a plurality of syrup containers, a secondary cooling bath in which said syrup containers are partially immersed, and means operable in response to flow of water in said pipe line for causing a positive circulation from said main bath and into said secondary bath.

11. The invention as defined in claim 10 wherein a rotary agitator is immersed in said main bath, and said means rotates said agitator.

12. In a liquid dispensing apparatus, a cooling bath, a pipe line for the liquid to be dispensed, partially immersed in said bath, a rotor positioned in said pipe line and operated by liquid flow therein, a pump immersed in said bath and operated by said rotor, the inlet and outlet of said pump communicating with said bath at spaced points, and a rotary bath agitating fan immersed in said bath and operated by said rotor.

13. The method of cooling liquids to be dispensed comprising immersing the liquid conducting means in a bath, refrigerating said bath, and agitating said bath by flow of the liquid.

14. The method of cooling liquids to be dispensed from separated sources from a single bath cooled by a refrigerating unit, which consists in causing the flow of one of said liquids to simultaneously maintain the temperature substantially uniform at all points and set up a circulation from said bath to the source relatively remote therefrom.

In testimony whereof I affix my signature.
WILLIAM E. LEIBING.
